Harley & Maxwell, Ventilating Ships.

Nº 11.669.

Patented Sept. 12, 1854.

UNITED STATES PATENT OFFICE.

JOS. L. HARLEY AND SAM'L. MAXWELL, OF BALTIMORE, MARYLAND.

VENTILATING SHIP-TIMBERS.

Specification of Letters Patent No. 11,669, dated September 12, 1854.

To all whom it may concern:

Be it known that we, J. L. HARLEY and SAM'L. MAXWELL, of the city of Baltimore and State of Maryland, have invented a new and useful Improvement in the Mode of Construction of Ventilators for Ships' Framing; and we do hereby declare that the following is a full, clear, and exact description of the same, reference being had 10 to the accompanying drawings, making a part of this specification.

We are aware a recent patent has been granted for an improvement having the same object in view with our invention, but 15 there are insuperable objections to its use and adoption, arising from its liability to have the cap of the tube forming the ventilator bent on one side by the accidental falling thereon of heavy rope or other articles 20 from above; the plan alluded to is further objectionable on account of requiring the stooping of the person and turning by hand of the stem and cap so as to shut or open the ventilator, whereas our caps are not injured by anything falling on them, as the 25 double action spring readily gives way, and the only effect is, the closing the tube; a further advantage we gain in the time and ease with which the cap may be closed 30 simply by the sailor passing along with his foot depressing the cap—which when down is retained in place by the single spring.

The ventilator may be described as follows: A A are the sides of a suitably sized 35 tube; B is a flange by which it may be secured to the plank shear through which the lower portion passes; C C a bridge supporting a ring D D in which slides the stem E carrying the cap F; upon the side of E is a 40 slight recess in which the spring α may be

compressed as the half length of the stem E reaches the ring D; b is a small stop to prevent the stem being entirely drawn out of the ring or socket; the dotted line d shows the cap closed, stem below the ring 45 and the spring expanded below it, thus securing the cap when down as the spring must be contracted to permit its rising.

There is a further objection to the invention alluded to, viz that of the half turn 50 necessary to keep it open, being accidentally thrown around by a rope dragging against the cap or stem thus throwing it off the step of the groove, and a consequent dropping of the cap results; and further objection is 55 the absolute necessity of giving the required half turn to the stem to close it securely; all of these objections we have by great simplicity avoided, as the only effect of a rope touching the cap and stem is to throw 60 it around, the spring maintaining it open or shut with certainty.

Having described our invention what we claim and desire to secure by Letters Patent is—

65 Constructing a ventilator for ships' frame, consisting of the tube A, cap F, fitting thereon, sustained by means of the double action spring α on the stem E, by which the cap is kept open or securely closed when down, in 70 the manner set forth.

In testimony whereof we have hereunto signed our names before two subscribing witnesses.

JOS. L. HARLEY.
SAM'L. MAXWELL.

Witnesses:

ROBERT WIER,
J. G. RAMSAY.
